DESIGN FOR A SIGNBOARD OR SIMILAR ARTICLE

George W. Lehman, Wheeling, W. Va., assignor to Ohio Valley Advertising Corporation, Wheeling,
W. Va., a corporation of West Virginia

Application September 19, 1935, Serial No. 58,620

Term of patent 7 years

To all whom it may concern:

Be it known that I, George W. Lehman, a citizen of the United States of America and a resident of Wheeling, county of Ohio, and State of West Virginia, have invented a new, original, and ornamental Design for a Signboard or Similar Article, of which the following is a specification, reference being had to the accompanying drawings forming part thereof, in which—

1; and

Fig. 1.

I claim—

The ornamental design for a signboard or similar article substantially as shown.

GEORGE W. LEHMAN.
